UNITED STATES PATENT OFFICE.

WILLIAM A. MILLER, OF COLUMBUS, OHIO.

DESIGN FOR AN AUTOMOBILE-TIRE.

52.959.

Specification for Design.

Patented Feb. 4, 1919.

Application filed November 29, 1918. Serial No. 264,749. Term of patent 14 years.

To all whom it may concern:

Be it known that I, WILLIAM A. MILLER, a citizen of the United States, residing at Columbus, in the county of Franklin and State of Ohio, have invented a new, original, and ornamental Design for Automobile-Tires, of which the following is a specification, reference being had to the accompanying drawing, forming part thereof.

Figure 1 is a fractional edge view of an automobile tire, showing my new design.

Fig. 2 is a transverse sectional view of the tire.

I claim:

The ornamental design for an automobile tire, as shown.

WILLIAM A. MILLER.
